HANDBAG CLOSURE CLASP

Etienne Aigner, New York, N.Y., assignor to The Villager,
Inc., Philadelphia, Pa., a corporation of Delaware

Filed Sept. 27, 1967, Ser. No. 8,758

Term of patent 14 years

U.S. Cl. D87—2
Int. Cl. D8—03

FIG. 1

FIG. 3

FIG. 1 is a front elevational view of a handbag closure clasp showing my new design;

FIG. 2 is a side elevational view thereof; and
FIG. 3 is a top plan view thereof.

I claim:

The ornamental design for a handbag closure clasp, substantially as shown.
